RECIPE FILING CABINETS
Helen Punzel, 208 E. Wisconsin Ave.,
Milwaukee, Wis. 53202
Filed Nov. 24, 1965, Ser. No. 509,561
1 Claim. (Cl. 129—43)

This is a continuation-in-part of my application Serial No. 363,326, filed April 20, 1964, now abandoned.

My invention relates to filing cabinets and more particularly to filing cabinets for filing recipe cards or the like.

The object of my invention is to provide a filing cabinet in the form of a compact unit to accommodate recipes in card form.

Another object of my invention is to provide a filing cabinet that permits separating the recipe cards into specific groups, by means of adjustably supported index members.

Another object of my invention is to provide a filing cabinet that has a cover with an overlying snap flange, on the end opposite the hinged end, to securely grasp an outer wall of the cabinet so that the cover is firmly in place when in the closed position; the snap flange also providing a means which may be grasped by the thumb and forefinger for ease of opening.

Still another object of my invention is to provide a device of the character described that permits any one of the recipe cards to be supported in a convenient manner, for visible observation during use.

A still further object of my invention is to provide a filing cabinet that is equipped with a hingedly supported cover that is adjustable to an angular position for use.

The device illustrated, described, and claimed herein, provides a single compact unit, that supports a plurality of recipe cards which are sorted, arranged, and separated into various specific groups, while having a hingedly supported cover that may be angularly adjusted and supported for easy access to the interior of the unit and at the same time conveniently display a recipe card for reading by the user.

The device constituting my invention is simple in construction, economical to manufacture and highly efficient for the purpose for which it is intended.

Other and further objects of my invention will become more apparent from the following specification and claim when taken in conjunction with the accompanying drawings, in which:

FIGURE 1 is a perspective view of the entire assembled unit in a closed, or sealed position;

FIGURE 2 is a top view of the cabinet with the cover in the closed position;

FIGURE 3 is a view taken along the line 3—3 of FIGURE 2;

FIGURE 4 is a plan view of the cabinet with the cover removed showing inwardly disposed vertical serrations for supporting laterally disposed index members;

FIGURE 5 is a cross-sectional view of the cabinet and also showing the cover raised into an angular display position to display a recipe card in a convenient position for observation by the user;

FIGURE 6 is a cross section taken along the line 6—6 of FIGURE 3;

FIGURE 7 is an enlarged cross-sectional view of the latch head construction of the top of the front panel of the cabinet designed to be engaged by the snap flange on the cover;

FIGURE 8 is an enlarged fragmentary view of a notch provided in the side panel of the cabinet which the cover engages when in the open position;

FIGURE 9 is a cross-sectional view taken along the line 9—9 of FIGURE 4; and

2

FIGURE 10 is an enlarged cross-sectional view of one of the bottom corners of the cabinet shown in FIGURE 5.

Similar characters of reference indicate corresponding parts throughout the various views.

Referring specifically now to the drawings, the character 10 shows a file cabinet body of rectangular contour, having a bottom plate 11, having indentations 5 in each corner to provide protruding supports 6 to which may be secured semi-circular legs 7 of a high friction material such as rubber or felt to prevent sliding of the cabinet on the plane that supports it. A pair of side walls 12 and 12', and front and rear vertical plates or sections 13 and 13', respectively, complete the main elements. The rear section 13' is equipped with hinge brackets 14a, which may be integrally formed therewith for supporting a cover assembly, consisting of a rearward section 15, supported by means of the hinge arms 14 frictionally received in hinge brackets 14a on the rear cabinet plate 13', and a forward section 16, which is hingedly attached to the section 15, by means of the hinge 17. Sections 15 and 16 may be hingedly attached by a simple pin although preferably it is attached by means of a living hinge. The hinge axis is preferable at the upper surface of the cover. Both of the cover sections 15 and 16 are provided with downwardly projecting flanges 18, which are adapted to overlay the upper portions of the sides 12 and 12' for the guidance and support of the cover. A flange 18' is provided at the front of the box so that a minor portion of the front surface of the front panel 13 is also overlain. The cover panel 16 simply rests upon and flange 18' overlies the upper edge of the front panel 13. Flange 18' has secured thereto tab 2 which may be grasped for easy opening of the covering assembly. The rear cover panel 15 is formed so that no depending flange similar to the flange 18' is provided. The axis of hinge 14 is positioned on a level no higher than that of hinge 17, and preferably slightly below the axis of hinge 17. The flanges 18 are shown beveled at 19, to permit the cover to be placed in an angular position shown in FIGURE 5. The beveled surfaces of the flanges are so angularly related to the upper surface of their cover sections that they abut against one another to provide a stop for the hinging action of the cover and limit movement to a position where the front section is slightly inclined to the vertical as shown in FIGURE 5. In this position the two cover sections have a generally inverted V-shaped relation. The upper edges of the side panels 12 and 12' have notches 3 formed therein at the position corresponding to the position of the lower or outer edge of the front cover section 16 when in the generally upright position as illustrated in FIGURE 5. These notches or indentations may be formed in the upper edges of the side panels 12 and 12' so as to receive the flange 18' of the front cover panel 16 and prevent accidental dislodgment when in the generally upright position. These notches are preferably of V-shape and are of sufficient size so as to receive flange 18' of cover panel 16 as illustrated in FIGURE 8.

The forward section 16 of the cover assembly has flange 18', as heretofore described, with a raised edge 20 in relation to the cover panel 16. This raised edge 20 provides a retaining ledge for receiving and retaining a recipe card 21, thereby providing support and convenient observation for a card for a particular or specific recipe being prepared by the user. It is at once apparent that raised edge 20 may be integrally formed with flange 18' or may comprise a separate element secured to the upper surface of flange 18' as by means of glue, solder, etc.

Flange 18' has an L-shaped configuration in cross section so as to form a snap fit with the uppermost edge 4 of front panel 13, this edge 4 having a slightly thicker

cross section than the remainder of the panel 13 as illustrated in FIGURE 7. For reasons of economy it is preferred that the edge 4 be formed integral with front panel 13, although a separate element secured to panel 13 could be utilized to obtain the snap-action fit with cover panel 16 when same is in the closed position.

The tab 2 secured to flange 18' serves as a handle for the cover, a turning force applied to the lower edge of the tab, accompanied by a rearward pushing force disengaging the snap fit between flange 18' and uppermost section 4 of front panel 13 causing a sliding movement of the front section rearwardly on the sides 12 and 12'.

Since overlying flange 18' is provided in overlying relation to the front panel 13, the cover may be opened by grasping tab 2 with the thumb and forefinger and exerting a pushing force directly upwardly and then toward the rear of the cover in which case the cover moves naturally to the angular upright disposition. The cover is opened to a point just beyond notches 3 in side panels 12 and 12' and flange 18' allowed to nest in notches 3 to hold the cover in the open position.

The vertical side walls 12 and 12', are equipped with internal vertical spaced ribs 23 to form channels or grooves shown at 22, to accommodate and guide the card members 21. Ribs or channels 23 may be constructed of rigid or semi-rigid sheet material such as metal, plastic or cardboard and separately secured to the inside surface of side panels 12 and 12'. However, it is preferred that they be formed unitarily with the side panels 12 and 12' as by machining or molding. The ribs 23 extend from the approximate bottom 11 of the cabinet, and in the preferred embodiment, terminate at a point distant from the top of the cabinet having a sloping upper surface with respect to the side panels as depicted in FIGURE 3 to permit ready access to the index cards they laterally support. The cards 21 are preferably of a smaller width than the inside dimensions of cabinet 10, so that the cards are conveniently removed. Index members (not shown) of a greater height than the cards 21 may be conveniently positioned so as to separate the cards into groups or categories under any one index card. The entire group of cards thus separated may be withdrawn and positioned on raised edge 20 for study by the user.

From the above description, it will become apparent that a device constituting my invention, consists of a compact unit in which recipe cards may be stored. It also provides a means of separating the cards into various groups or categories that are identified by the index members, which members slidably engage the channels or serrations on the inner surface of the side members forming an integral part of the file. These index members may have upwardly extending tabs arranged in any conventional manner to accommodate identification means.

When the device is in use, the sectional hinged cover may be moved to the angular position, such as is shown in FIGURE 5, as by manipulation of the cover by tab 2. Flange 18' in conjunction with edge 20 then serves as a edge and any one of the recipe cards may be disposed within the ledge where it is visible at all times while the product described on the recipe card is being prepared. For access to the rearward portion of the cabinet, the entire cover may be rearwardly moved, as by manipulation of the flange 18' past the notches 3 or the position shown in FIGURE 5.

It is preferred to make the article from molded plastic such as polypropylene. The two sections 15 and 16 may then be unitarily molded while connected by a thin section of molded material. Hinge arms 14 may also be

connected to section 15 by a thin section of molded material. These thin sections enable pivotal movement of the two cover sections and pivotal movement of the cover section 15 relative to the rear wall.

Whereas I have shown and described certain operative forms of the invention, it should be understood that this showing and description should be taken as illustrative of the invention and that those modifications falling within the spirit of the invention are reserved as they fall within the scope of the hereinafter appended claim.

I claim:

A recipe card indexing assembly including a rectangular body defined by side panels, front and rear panels and a bottom panel, the inner faces of said side panels having a plurality of evenly spaced projections thereon to define a plurality of evenly spaced and upwardly open slots adapted to receive a plurality of cards to be positioned within said body whereby opposite ends of each card being positioned is disposed within opposed seats on opposite side panels; a sectional cover hinged to the rear panel and movable over the upper portion of said body, said cover being comprised of hinged sections, one of said section being adapted to overlie the rear portion of said body in the closed position of said cover and the other section being adapted to overlie the forward portion of said body in the closed position of said cover, said sections being hinged together to enable an upstanding inverted generally V-shaped disposition of said sections with the forward edge of the forward section resting in notches hereinafter defined in said side panels intermediate the ends thereof; each cover section having downwardly extending lateral flanges at the sides thereof and overlying the sides of the body in the closed position, said lateral flanges having beveled surfaces adjacent the hinge axis of said sections, said beveled surfaces abutting against one another and limiting movement of said section to said V-shaped disposition thereof when said cover is moved to said disposition while thereby exposing a substantial area of said body; said front cover section resting on the upper portion of said front panel and having a downwardly extending front flange overlying said front panel, said front flange having a projection thereon extending above the plane of said cover section to thereby form a ledge adapted to receive at least one card to be confined within said body, said front flange also having a tab thereon whereby said cover sections may have exerted thereto a push-pull force, said front flange and the uppermost edge of said front panel each having a configuration to engage each other in snap-action relationship; said side panels having notches in the upper edges thereof so as to receive and hold the front flange of the front cover section with the portions of the lateral flanges outside the side panels of the box.
